UNITED STATES PATENT OFFICE.

EMILIE DE NICOLAS DU PLANTIER, OF PARIS, FRANCE.

IRRIGATOR HAVING A CONSTANT TEMPERATURE.

No. 922,810.

Specification of Letters Patent.

Patented May 25, 1909.

Application filed August 2, 1907. Serial No. 386,824.

To all whom it may concern:

Be it known that I, EMILIE DE NICOLAS DU PLANTIER, a citizen of the French Republic, and resident of Paris, France, have invented certain new and useful Improvements in Irrigators Having a Constant Temperature, of which the following is a specification.

This invention relates to new and useful improvements in irrigators and it is an object of the invention to provide a novel device of this kind wherein a constant or even temperature is maintained.

The well known irrigators do not maintain the temperature of the water, as there is a more or less rapid deterioration of the heat of the bath, especially when the flow of the liquid is continued. It follows therefrom that it is only possible to administer vaginal irrigations, which are too rapid for producing a sedative result, and with the outflow of the liquid, the treated organs are exposed to diminishing temperatures. This is a serious drawback.

It is the object of the invention to obviate these disadvantages and present a device whereby the irrigating waters are maintained at a constant or even temperature throughout the entire operation.

It is also an object of the invention to control the flow of liquid.

A further object of the invention is to provide a device of the character described which will be simple in construction, efficient in practice and economical to manufacture.

With the foregoing and other objects in view, the invention consists in the details of construction and in the combination and arrangement of parts to be hereinafter more fully set forth and claimed.

In describing the invention in detail, reference will be had to the accompanying drawings forming part of this specification wherein like characters denote corresponding parts in the several views, and in which—

Figure 1, illustrates a front elevation of the device. Fig. 2, is a vertical section of the same. Fig. 3, is a view of the device mounted on a support. Fig. 4, is a detail view of the supporting mechanism. Fig. 5, is a view partly in elevation and partly in section of the draft controller. Fig. 6, is a view in top plan of a detail of Fig. 5.

In the drawings 1, denotes a cylindrical receptacle having a bottom 2, and a removable cover 3. Projecting through the bottom 2

and the top 3, and arranged centrally of the receptacle 1, is a chimney 4, having at its base the grating 6. The chimney may be closed at its top by the cap 5. A combustible 60 preferably in the nature of a slow burning artificial coal brick, is supported by the grate 6.

The receptacle 1, is intended to be filled with water and is provided with the thermometer 7, and the water gage 8, the purposes of which being, it is thought, clearly apparent.

A draft controlling device 9, for the chimney 4, which consists of a plate, is arranged 70 below the combustion-chamber grate 6, and has a dished or depressed portion 22 for receiving the ash from said grate, said plate being slidably supported in guide-ways 23 secured to the bottom 2 of the receptacle 1. 75 Said plate extends outwardly through an opening in the base-member or skirt of the receptacle and has a finger-piece 10 for the ready grasping and moving of said plate as in regulating the draft or removing the ash. 80

The water heated within the receptacle leaves the latter through the pipes 12, which connect with the pipe 15, leading to a suitable cannula (not shown). The flow through the pipes 12, with the pipe 15, is controlled 85 by the valve 13, operated by the key 14, extending to one side of the receptacle.

The receptacle 1, is provided with the handles 16, which facilitates its application to, or removal from, its support which is illustrated in the drawings as a tripod (see Figs. 3 and 4).

The standard 19, of the tripod, has the telescoping extension 18, the upper end of which is forked to form bearings for the 95 trunnions 17 of the receptacle 1. The movement of the section 18, for the purpose of adjustment, is controlled by the screw 20.

In Fig. 5, only one discharge pipe 12 is employed which is controlled by a cock 13 100 and its key 14.

What I claim is:

1. An irrigator comprising a liquid containing receptacle having an intermediate bottom forming member upraised or removed from its supporting edge and a central chimney member having its upper end extending beyond the top of said receptacle to serve as a stack, said chimney member depending below said intermediate bottom 105 forming member and equipped with a grate, said chimney member depending portion 110

having arranged therein below the grate a dished ash receiving plate member, also adapted to control the air supply to the grate.

5 2. An irrigator comprising a liquid containing receptacle having an intermediate bottom forming member removed from its supporting edge and a central chimney member having its upper end extending beyond 10 the top of said receptacle to serve as a stack, said chimney member depending portion having arranged therein below the grate a

dished ash receiving plate member, also adapted to control the air supply to the grate, and a valve equipped pipe leading 15 from said intermediate bottom forming member and having connected thereto a hose.

In testimony whereof I have hereunto set my hand in presence of two witnesses.

EMILIEN DE NICOLAS DU PLANTIER.
